H. A. CARPENTER,
STAND PIPE CLEANING MEANS,
APPLICATION FILED APR. 25, 1914.

1,135,498.

Patented Apr. 13, 1915.

UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

STAND-PIPE-CLEANING MEANS.

1,135,422

Specification of Letters Patent. Patented Apr. 13, 1915.

Application filed April 25, 1914. Serial No. 834,429.

To all whom it may concern:

Be it known that I, HENRY A. CARPENTER, a citizen of the United States, residing at Sewickley, in the county of Allegheny and State of Pennsylvania, have invented certain new and useful Improvements in Stand-Pipe-Cleaning Means, of which the following is a specification.

In the manufacture of gas from coal in carbonization apparatus to which the present invention relates, the gas is passed from the retorts of a bench into stand-pipes, and thence into a gas conduit or main, which latter may be located either at the top or at the bottom of the stand-pipes. Under some conditions, considerable foreign matter carried by the gas will adhere to the interior of the stand-pipes, and, in order to maintain an efficient operation of said pipes, the material should be removed therefrom. It is desirable that the stand-pipes be cleaned without stopping the flow of gas from the retorts to the stand-pipes and through the stand-pipes to the main.

The prime object of the present invention is to provide a new and improved apparatus for cleaning stand-pipes of the character above described.

In the accompanying drawing, which illustrates an application of my invention, Figure 1 is a vertical sectional view showing a portion of a stand-pipe, a main or gas conduit, and the cleaning apparatus shown in connection therewith; Fig. 2 is a horizontal sectional view, the section being taken one line 2--2 of Fig. 1; Fig. 3 is a perspective view of the cleaning tool employed; Fig. 4 is an elevational view particularly showing the clamping means; and Fig. 5 is a sectional detail view of a part of the clamping mechanism.

In the illustrated embodiment of my invention, I have deemed it unnecessary to show more than a portion of a single stand-pipe and a portion of a gas conduit or main into which the stand-pipe projects. It should be understood, however, that in practice, a plurality of stand-pipes extend into the main.

Referring to the drawing, 1 designates the upper portion of a stand-pipe of rectangular form in cross section, and 2 a main, cooling chamber or conduit into which the stand-pipe projects. As illustrated, the member

2 is provided with an opening 3 in line with the opening of the stand-pipe. Secured to the main 2 and surrounding the opening 3 thereof is a valve-casing 4 in which a valve 5 operated by a valve stem 6 is located. The purpose of the valve is to prevent the escape of gas through opening 3 when closed, and when open to permit access to the stand-pipe 1 through the main 2 when it is desired to clean the stand-pipe, or for any other purpose.

The cleaning apparatus, as shown and as preferred, comprises a casing 7 adapted to be supported on and securely clamped to the valve-casing 4.

During the cleaning operation, a tight joint should be maintained between the valve-casing and the tool-casing to prevent the escape of gas therethrough. As illustrated, the valve-casing is provided with a supporting flang or ledge 8 having a smooth ground contacting face on which the lower smooth edge 9 of the tool-casing is supported. The valve-casing and the tool-casing are provided with co-acting clamping means whereby, when the tool-casing is placed in position on the valve-casing, the lower contacting edges of the tool-casing may be drawn into close contact with the supporting ledge 8.

The clamping means illustrated are of such a character as to effect a slight sliding action of the tool-casing upon the supporting ledge 8 of the valve casing, when the said clamping means are moved into clamping position by means of the eccentric levers 10.

11 designates eccentrics supported by the tool-casing and designed to coöperate with side bars 12, which latter are connected at one end by a cross bar 13. The three-sided member, made up of the side bars 12 and the cross bar 13, is pivotally connected with apertured lugs 14, the latter being secured to the valve-casing, by means of a laterally extending pin or rod 15 adapted to be passed through the apertured lugs 14 and apertured projections 16 of the bars 12. The free ends of members 12 are adapted to be engaged by links 17 pivotally supported from the valve-casing.

After the tool-casing has been placed in operative position on the valve-casing, as above described, the links 17 are placed over

the free ends of rods 12 and the eccentric actuating levers 10 moved to securely clamp the two casings together.

Supported within the casing 7 by means of a wire rope 18 is a cleaning tool 19. Cleaning tool 19 is preferably of the form shown when employed for cleaning stand-pipes having a rectangular cross section as the pipe shown in the drawing. This tool 10 comprises a hollow metallic structure of considerable length and weight having at its lower end cutting edges 20 and preferably formed open at its top and bottom as indicated by the numerals 21 and 22. In addition to the openings 21 and 22, I have provided an opening 23 in each side face thereof, thereby permitting gas from the retorts to have practically an uninterrupted flow through the stand-pipe during the operation 15 of cleaning the pipe. The tool is designed to be raised and lowered into the stand-pipe by any suitable means connected with the operating cable 18, and for the purpose of preventing the escape of gas through the cable opening of the tool-casing, I provide a 20 stuffing-box 24.

In practice, the cleaning tool is slightly smaller in cross section than the corresponding section of the interior of the stand-pipe 30 into which it is adapted to be entered, and is of sufficient length to bridge the space between the lower end of the cleaning tool casing and the stand-pipe, or of a length sufficient to permit of the lower end of the tool 35 being introduced into the stand-pipe before its upper portion leaves the tool casing. The tool is connected with the cable by means of a spider 25.

It will be noted that the side openings 23 40 of the tool will permit the gas from the retorts to pass therefrom into the stand-pipe, even though the tool is directly in line with the horizontal ports connecting the several retorts, not shown, and the stand-pipe, and 45 that the tool is of such a character as to permit gas from the retorts below the tool to pass upwardly therethrough without stoppage.

While the construction illustrated contemplates taking off the gas from the retorts and passing the same upwardly into a conduit, it is evident that the conduit may be placed at the lower ends of the stand-pipes and the gas conveyed downwardly through the 50 stand-pipes. In the latter case, the valve-casing may be secured directly to the upper end of the stand-pipe and the cleaning apparatus clamped thereto in substantially the same manner as above described and as illustrated.

What I claim is:—

1. The combination with a gas retort stand-pipe, of cleaning means therefor including a detachable casing and a tool, means for entering the tool into the stand-pipe, and

means constituting a gas-tight connection between the stand-pipe and said casing.

2. The combination with a gas retort stand-pipe, and closure means therefor, of cleaning means for the stand-pipe including a casing and a tool, the latter adapted to be entered in the stand-pipe, said casing and closure having co-operating means to prevent communication between the gas and atmosphere during the cleaning operation.

3. The combination with a stand-pipe, a cleaning tool therefor, a valved passage through which the tool is adapted to be entered and withdrawn, and a tool inclosing casing having a removable gas-tight connection with said passage outwardly from the valve.

4. The combination with a gas retort stand-pipe, of means effective to clean the stand-pipe during the passage of gas therethrough including a casing in communication with the stand-pipe and a tool having an opening to permit of the passage of gas through the tool, and means for lowering the tool from the casing into the stand-pipe.

5. The combination with a gas-retort stand-pipe and closure means therefor, of a stand-pipe cleaning means including a tool, and means for lowering the tool through the closure means into the stand-pipe.

6. The combination with a stand-pipe and valved closure means therefor, of stand-pipe cleaning means including a tool, and means for lowering the tool through the valved closure means into the stand-pipe.

7. The combination with a stand-pipe, of a conduit in communication with an end of the stand-pipe and having a stand-pipe cleaner-receiving opening in line with the stand-pipe, a valve casing bounding said opening, a tool-casing, a cleaning-tool, means for clamping the tool-casing to the valve-casing, and means for lowering the tool from the casing into the stand-pipe.

8. The combination with a stand-pipe, of a conduit into which the upper end of the stand-pipe enters and having a stand-pipe cleaning-tool receiving opening in line with the stand-pipe, a valve-casing bounding the opening, a tool-casing secured to the valve-casing, and a cleaning-tool adapted to be passed through the opening and entered in the stand-pipe.

9. The combination with a stand-pipe, of a gas conduit in communication with an end of the stand-pipe and having a tool-receiving opening in line with the stand-pipe, a tool-casing, a cleaning tool of sufficient length to bridge the space between the tool-casing and the stand-pipe and adapted to be passed through the opening in the conduit and entered in the stand-pipe.

10. The combination with a stand-pipe, of a valve-casing in communication therewith, a valve, a tool-casing, means for securing the

tool-casing to the valve-casing, and a stand-pipe cleaning tool adapted to be entered into the stand-pipe through the valve-casing.

11. The combination with a stand-pipe, of 5 a valve-casing in communication therewith, a valve, a tool-casing, coacting means on the respective casings for clamping them together, and a stand-pipe cleaning tool adapted to be entered into the stand-pipe through 10 the valve-casing.

12. The combination with a stand-pipe and closure means therefor, of stand-pipe cleaning means including a casing and a tool, and means for securing the casing to

the closure means to effect a gas tight joint 15 therebetween.

13. The combination with a stand-pipe and closure means therefor including a casing, of stand-pipe cleaning means including a casing and a tool, said casings placed end 20 to end, and coacting clamping means on said casings.

In testimony whereof I affix my signature in presence of two witnesses.

HENRY A. CARPENTER.
